US00D980848S

(12) **United States Design Patent** (10) **Patent No.:** **US D980,848 S**
Cullum et al. (45) **Date of Patent:** **** Mar. 14, 2023**

(54) **DISPLAY SCREEN OR PORTION THEREOF WITH GRAPHICAL USER INTERFACE AND ICON**

(71) Applicant: **StreamLabs, Inc.**, Whitehouse Station, NJ (US)

(72) Inventors: **Callie Cullum**, Atlanta, GA (US); **Sam Elia**, Atlanta, GA (US); **Ben Robinson**, Atlanta, GA (US); **Allison Applegate**, Atlanta, GA (US)

(73) Assignee: **StreamLabs, Inc.**, Whitehouse Station, NJ (US)

(**) Term: **15 Years**

(21) Appl. No.: **29/776,331**

(22) Filed: **Mar. 29, 2021**

Related U.S. Application Data

(60) Division of application No. 29/676,124, filed on Jan. 8, 2019, now Pat. No. Des. 916,731, which is a continuation of application No. 29/643,926, filed on Apr. 12, 2018, now Pat. No. Des. 871,431.

CLAIM

We claim the ornamental design for a display screen or portion thereof with graphical user interface and icon, as shown and described.

DESCRIPTION

FIG. 1 is a front view of an embodiment of the claimed design of a display screen or portion thereof with a graphical user interface; and,

FIG. 2 is a front view of another embodiment of the claimed design of a display screen or portion thereof with a graphical user interface.

The outermost broken lines in the Figures illustrate a display screen or portion thereof and form no part of the claimed design. The other broken lines in the Figures illustrate portions of the graphical user interface that form no part of the claimed design.

1 Claim, 2 Drawing Sheets
